UNITED STATES PATENT OFFICE.

CHARLES H. ANDERSON, OF OKLAHOMA, OKLAHOMA, ASSIGNOR TO NORTH & JUDD
MANUFACTURING COMPANY, OF NEW BRITAIN, CONNECTICUT, A CORPORATION.

DESIGN FOR A HARNESS-SPREADER.

● 40,569.

Specification for Design.

Patented Mar. 8, 1910.

Application filed November 24, 1909. Serial No. 529,842. Term of patent 14 years.

To all whom it may concern:

Be it known that I, CHARLES H. ANDERSON, a citizen of the United States, residing at Oklahoma city, in the county of Oklahoma and State of Oklahoma, have invented a new, original, and ornamental Design for Harness-Spreaders, of which the following is a specification, reference being had to the accompanying drawing, forming part thereof.

The figure is a perspective view of a harness spreader, showing my new design.

I claim:—

The ornamental design for a harness spreader, as shown.

CHARLES H. ANDERSON.
